UNITED STATES PATENT OFFICE.

FRANKLIN STELTZ, OF POTTS TOWN, PENNSYLVANIA.

DESIGN FOR A SOCKET FOR MEAT-SUPPORTERS.

SPECIFICATION forming part of Design No. 19,587, dated January 14, 1890.

Application filed December 21, 1889. Serial No. 334,564. Term of patent 3½ years.

To all whom it may concern:

Be it known that I, FRANKLIN STELTZ, a citizen of the United States, residing at Pottstown, in the county of Montgomery and State 5 of Pennsylvania, have invented a new and useful Design for a Socket for Meat-Supporting Sticks, of which the following is a specification.

The invention relates to a new and original design of socket for meat-supporting sticks.

10 In the drawings, Figure 1 is a perspective view showing my new design of socket for meat-supporting sticks. Fig. 2 is a longitudinal sectional view. Fig. 3 is a rear elevation.

Referring to the drawings, 1 designates a 15 plate having slightly curved and tapering sides 2 and 3 and provided with screw-openings 4. The plate 1 has extending out laterally from its center a tubular portion 5, which has projecting longitudinally therefrom a 20 semi-cylindrical lip or extension 6.

7 and 8 are triangular flanges, the former of which is smaller and is arranged above the tubular portion, and the latter one is arranged

beneath the tubular portion and the semi-cylindrical extension 6 and lies in the same plane 25 as the smaller flange 7.

9 is a sausage-supporting stick.

Having described my invention, what I claim is—

The design for socket herein shown and described, the same consisting of the plate 1, having screw-openings 4, the tubular portion 5, extending out laterally from the center of the plate, the semi-cylindrical lip or extension projecting longitudinally from the tubular 35 portion, and the triangular flanges 7 and 8, arranged above and below the tubular portion 5 and lying in the same plane, as set forth.

In testimony that I claim the foregoing as my own I have hereto affixed my signature in 40 presence of two witnesses.

FRANKLIN STELTZ.
